TOWEL BAR

David P. Zagaroli, Hickory, N.C., assignor to Ajax Hardware Corporation, City of Industry, Calif.

Filed Mar. 14, 1973, Ser. No. 341,048

Term of patent 14 years

Int. Cl. D6—06

U.S. Cl. D6—99

FIG. 1 is a front elevational view of a towel bar showing my new design;

FIG. 2 is a top plan view thereof;

FIG. 3 is a rear elevational view thereof; and

FIG. 4 is an end elevational view thereof.

Portions of the towel bar have been omitted from FIGS. 1, 2 and 3 for convenience of illustration.

I claim:

The ornamental design for a towel bar, as shown and described.
